UNITED STATES PATENT OFFICE.

SAMUEL KANNER, OF NEW YORK, N. Y.

RAZOR-STROPPING MACHINE.

Application filed August 18, 1919. Serial No. 318,354.

To all whom it may concern:

Be it known that I, SAMUEL KANNER, a citizen of the United States, and a resident of New York city, in the county of New York and State of New York, have invented certain new and useful Improvements in Razor-Stropping Machines, of which the following is a specification.

The invention pertains to razor stropping machines of the class comprising a frame through which a strop is threaded and is to be alternately pulled at its ends, and a blade-holder located between the reaches of the strop and adapted to alternately carry the blade thereto as said reaches are alternately pulled outwardly in line with their length, the blade moving to one reach as said reach is pulled outwardly and to the other reach when it is pulled outwardly.

One object of the invention is to provide an efficient stropping machine possessing novel means for rocking the blade-holder from one side to the other as alternate reaches of the strop are pulled, and cooperative mechanism for causing said holder to travel in line with its length while the blade is against the alternately outwardly moving reaches of the strop, thereby enabling the blade to receive substantially the same treatment as it would if stropped by hand.

The present invention resides more particularly in the novel construction, relation and arrangement of parts constituting the several frames of the machine, it having been found to be highly desirable that machines of this class be durable and inexpensively constructed and also of such character as to remain efficient for a very considerable period. The framing of the present machine consists of three main sheet metal parts, each being in one integral piece and efficiently cooperating with one another and with the other features of the machine to provide a machine of great efficiency and durability.

Referring to the drawings:

Fig. 1 is a central vertical section through a razor blade stropping machine embodying my invention, the section being on the dotted line 1—1 of Fig. 3;

Fig. 2 is a transverse section through the same, on the dotted line 2—2 of Fig. 1;

Fig. 3 is a vertical transverse section through the same, on the dotted line 3—3 of Fig. 1;

Fig. 4 is a vertical section through the same, partly broken away, corresponding

with Fig. 2, but illustrating the parts of the mechanism in a different position;

Fig. 5 is a perspective view of a rockable frame over which the strop is alternately pulled at its respective ends, the dotted lines indicating the blank from which said frame is formed;

Fig. 6 is an elevation of a blank from which the blade-holding frame and connected parts are formed;

Fig. 7 is a sectional view, partly broken away, lengthwise through the blade-holder, and

Fig. 8 is a section, on a larger scale, 70 through the same, taken on the dotted line 8—8 of Fig. 7.

In the drawings, 10 designates the general exterior frame of the machine, 11 the strop, 22 an interior three-sided oscillatory frame 75 journaled between the sides 13 of the main general frame, 12 a rockable friction frame over which the strop 11 is folded and which is journaled between the vertical sides of the frame 22, 14 a worm or screw-threaded shaft 80 journaled between the sides 13 of the main frame on a rod 136 whose ends are riveted in said sides 13 and upon which rod the ends of the frame 12 are pivotally mounted, and 15 a sheet metal frame fashioned at its middle 85 portion to engage said worm or spirally grooved shaft and also to afford a blade-holder 16 adapted to receive the razor-blade 17 to be sharpened.

The exterior frame 10 comprises in one 90 integral piece the parallel sides 13 and a connecting crown portion having a flat top 18 and downwardly diverging sides 19, said crown portion being adapted to receive within it and between said sides 19 a spring 95 20 whose ends are extended downwardly to engage the top 21 of the interior frame 22 composed of said top 21 and side members 23. At the central upper portion of the top 18 of the general frame is integrally 100 formed a loop 24 to receive a strap 25 by which the stropping machine may be connected with a hook or other restraining device. The sides 13 of the frame 10 are open 105 at their lower end portions, as at 26, and said sides are connected together at said open portion 26 by means of upper rods 27, lower rods 28 and guide-rods 29. The frame 10 is in one integral piece formed from sheet metal.

The interior frame 22 comprising the top 21 and sides 23 is also in one integral piece

of sheet metal and is rockably or pivotally supported between the upper portions of the sides 13 of the main frame on a transverse rod 30 which extends through the upper portions of said sides 23 and through the sides 13 of the main frame and is headed at its opposite ends, as shown in Fig. 1. The sides 23 of the frame 22 are, below the pivot rod 30, formed with arcuate slots 31, and 10 directly below said slots said ends 23 have central downwardly extending lower end portions 32 between which is mounted a rod 33, this rod 33 being a pivot and guide rod for the frame which affords the blade holder 16. The sides 23 are provided between the slots 31 and rod 30, with vertical slots 34.

The frame 22 is adapted to have a limited oscillatory movement on the pivot rod 30 and receives its movement from the rockable frame 12 whose side portions are equipped with pins 35 projecting into the aforesaid vertical slots 34. The frame 22 by reason of the action of the spring 20 against the top of the same and acting at the sides of the 25 slots 34 against the pins 35, serves the function of providing a spring resisting pressure of the razor-blade 17 against the reaches of the strop 11 and to normally maintain the blade-holder 16 in its central position, shown 30 in Figs. 2 and 3, between the reaches of said strop.

The arcuate slots 31 in the sides of the frame 22 receive through them the end portions of the rod or shaft 136 supporting the 35 rotatory worm-shaft 14, said ends of said shaft or rod 136 being suitably headed in the sides 13 of the frame 10 and said arcuate slots 31 permitting the frame 22 to have an oscillatory movement on the pivot-rod 30.

40 The rockable friction frame 12 is formed from one integral piece of sheet metal, as shown more particularly in Fig. 5, and comprises vertical side portions 36 having the pins 34 and arcuate or curved front and rear 45 bar-portions 37, between which said frame 12 is formed with an opening 38. The sides 35 of the frame 12 are also formed with bearing openings 39 through which the reduced ends 136 of the spiral shaft or worm 50 14 extend, and these openings 39 are in line with the arcuate slots 31 formed in the sides of the frame 22. The strop 11 is folded over the worm-shaft 14 and against the outwardly oppositely curved arcuate bar-portions 37 of the frame 12, as shown in Fig. 4, 55 and when one reach of the strop 11 is pulled it will rock the frame 12 in one direction and when the other reach of the strop is pulled it will rock said frame in the opposite direction. When the frame 12 is caused to 60 rock in one direction it will, through the pins 35, operate to rock the frame 22 in a reverse direction, as indicated by Fig. 4, said frame 22 then acting to compress the ends 65 of the spring 20 and thereby create a ten-

sion tending to reverse this movement of the frame 12 and compel said frame when the pull on the strop has ceased to carry the blade-holder 16 to a central position between the reaches of the strop.

The frame 15 is formed from a blank, shown in Fig. 6, which is folded around the worm-shaft 14 and at its then lower ends fashioned to provide the blade-holder 16 whose opposite sides converge downwardly, as usual, and enclose between them a spring 40 (Fig. 7) which serves to press against the upper edge or back of the razor-blade and force the cutting edge of said blade downwardly so that the same may be exposed and engage the strop. Those portions of the blank 15 which provide the blade-holder 16 are numbered 41, and said portions 41 at their facing end parts have flanges 42 which extend substantially at 85 right angles to the portions 41 and in the finished blade-holder lap upon one another and are secured together by rivets 43, as shown in Fig. 7. At the mouth-end of the blade-holder the flanges 42 are slit and pressed downwardly to form a loop 44 which engages one end of the spring 40 and serves to retain the spring in position. Above the blade-holder 16 the frame 15 is bent into cylindrical form, as at 45, to closely receive the rod 33, 90 and above the rod 33 the metal portion of the frame 15 has bars 46 closely and spirally wound upon the worm-shaft 14, the loops formed by the bars 46 being within the groove formed by the spiral thread of said shaft and 100 free to travel on said shaft during the employment of the device. The frame 15 is in one integral piece of sheet metal and is suspended from the worm-shaft 14 and rod 33, and that portion of the frame affording 105 the blade-holder 16 is in line with the openings 26 in the sides 13 of the frame 10. At its inner end the blade-holder 16 is formed with a stop 47 to arrest the blade when the same is inserted into the holder. I so proportion 110 the parts of the frame 15 that the lower edge of the blade-holder 16 is in near relation to the rods 27 when the device is in use and that the cutting edge of the blade will be engaged by the strop 11 slightly below the 115 rods 27, as indicated in Fig. 4, this arrangement permitting the strop to have an effective action on said cutting edge. The relation of the blade-holder 16 with regard to the rods 27 permits the lower edge of 120 said holder to receive a firm backing from said rods 27, while the strop below said rods is enabled to engage the cutting edge of the blade.

In the use of the device the razor blade 125 will be inserted in the holder 16 and the strop 11 will be pulled alternately at its opposite end portions, in a known manner. The traveling action of the strop upon the worm-shaft 14 effects the rotation of said 130

shaft and the consequent longitudinal travel of the frame 15, blade-holder 16 and blade 17, said blade-holder moving in one longitudinal direction when one reach of the strop 5 is pulled and in the other longitudinal direction when the other reach of the strop is pulled, with the result that during the stropping the blade is given an endwise movement.

10 An important feature of my construction of stropper resides in the fact that the worm shaft 14 has a long bearing on the rod 136 and is therefore assured of uniform movement for a long period of time. By heading 15 the rod 136 in the sides of the main frame said frame becomes strengthened, and by reason of said rod being stationary, the walls of the arcuate slots 31 have a fixed relation thereto, which was not the case heretofore 20 when integral ends of the worm shaft were mounted in small bearings in the main frame and became rapidly worn and irregular in movement.

What I claim as my invention and desire 25 to secure by Letters Patent, is:

In a razor strop of the character described, the combination of a strop to be pulled at alternate ends, a main frame, a spirally threaded shaft mounted therein, a 30 blade-holder frame comprising facing and

matching portions secured together and forming arms at the upper portion of the holder in engagement with the thread of said shaft and below the same laterally curved matching portions forming 35 a tubular sleeve and below said sleeve a pair of jaws adapted to releasably hold a razor blade, a pivotally hung friction frame engaged by the reaches of said strop below the top of said shaft, 40 a rockable frame pivotally mounted between the sides of said main frame and having sides and a rod connecting the same and lying within said sleeve and affording a guide for said blade holder frame, during its endwise movements, and means connecting said friction frame and said rockable frame so that motion may be imparted from said friction frame to said rockable frame and its 45 said rod when the reaches of the strop are 50 alternatively pulled, said rod being parallel with said spirally threaded shaft.

Signed at New York city, in the county of New York and State of New York, this 13th day of August, A. D. 1919.

SAMUEL KANNER.
